(57) **CLAIM**

The ornamental design for a furniture lattice, as shown and described.

DESCRIPTION

FIG. 1 is a front elevational view of my new design for a furniture lattice, showing it incorporated in a bed frame.

FIG. 2 is a left side elevational view thereof.

FIG. 3 is a rear elevational view thereof.

FIG. 4 is a right side elevational view thereof.

FIG. 5 is a top plan view thereof; and,

FIG. 6 is a bottom plan view thereof.

The broken line elements of the bed frame are for illustrative purposes only and form no part of the claimed design.
